DIFFERENTIAL ACTUATING MECHANISM

Daniel Broido, Barnet, England

Application December 26, 1951, Serial No. 263,176

6 Claims. (Cl. 235—60)

1

This invention relates to adding, accounting, calculating and like machines employing resiliently driven value-entering means.

In machines of the kind referred to the values to be entered are often represented by settable stops; value-entering reciprocating racks or similar devices are yieldingly driven on to the stops, the distance covered by the racks when moving from a fixed starting position on to the stops being representative of the values associated with the respective stops. These racks may be driven by springs or similar resilient means, and the total force of these springs or like means represents a major factor of the load to be overcome by the drive of the machine, inasmuch as these resilient means must be sufficiently powerful to drive the racks at a relatively high speed.

The main object of this invention is to devise an arrangement for driving value-entering racks and like means reliably at a high speed, and with a minimum of effort.

In some machines of the kind referred to the settable stops are mounted on a carriage shiftable denominational in relation to value-entering means; alternatively, the value-entering means and/or the registers controlled by the value-entering means may be displaceable transversely of the settable stops. In order to ensure a free movement of the carriage a clearance must be provided between the shiftable parts and the stationary parts of the machine.

An object of the invention is to provide a substantial gap between the value-representing stops and the reciprocating value-entering means when the latter are in a starting or retracted position.

Other objects will become apparent as the description proceeds.

With these objects in view, according to the present invention, a value-entering device for use in machines of the kind referred to having selectively settable stops representing numerical values comprises a plurality of reciprocating elements normally located in a starting position, the distance between any stop and the associated reciprocating element when the latter is in the starting position being representative of the value associated with the respective stop plus unity, a common driving member adapted to drive all said elements positively from the starting position through a distance substantially rep-

2

resentative of unity, and means for restoring the said elements positively into the starting position.

The device may further comprise resilient driving means associated with each of said elements and adapted to drive it yieldingly on to the respective settable stop.

In the accompanying drawings which illustrate a preferred embodiment of the invention:

10 Figure 1 is a longitudinal vertical section through the value-entering device substantially on line I—I of Figure 2,

15 Figure 2 is a transverse vertical section substantially on line II—II of Figure 1,

15 Figure 3 is a longitudinal vertical section substantially on line III—III of Figure 4 showing part of the operating mechanism, and

20 Figure 4 is a transverse vertical section on line IV—IV of Figure 3 also showing the operating mechanism.

In a preferred embodiment of the invention the value-entering means are in the shape of reciprocating sensing racks 20, Figs. 1 and 2, slidably mounted in guides 21—24. Each rack 20 is 25 adapted to operate a numeral wheel 19 of a totalizer fully described in the specification to my co-pending application No. 263,177, now Patent No. 2,628,029, the same numerals being used both in this co-pending specification and in the present application with reference to the same parts.

The values to be sensed by the racks 20 are represented by selectively settable stops shown somewhat diagrammatically in Fig. 1 as at 0—9. When raised into position indicated by dotted lines, any stop 0—9 is adapted to intercept the tip 26 of the respective rack 20 when the latter is moved by its spring 19 to the left as viewed in Fig. 1. It will be understood that there is a bank of stops 0—9 in association with each operative rack 20; alternatively, one stop may be settable to each position 0—9 in association with each operative rack 20. Stops 0—9 may be operated in various manners which are well known in the

40 art and immaterial for a proper understanding of the present invention; for instance, they may be set in the manner described in my prior British patent specification No. 577,330.

According to the present invention, the distance between the stops 0—9 and the racks 20

when the latter are in the starting position is determined in the following manner:

Assuming the rack movement required to move the associated totalizer element 10 through a distance representative of unity is what may be termed one step, the distance from the tip 26 of a rack in the starting position of Fig. 1 to a stop representing 0 is made equal to one step, that to a stop representing 1 is made equal to two steps, that a stop representing 2 is made equal to three steps, and so on; the distance from a rack to a stop representing 9 is ten steps. Thus, the distance between a rack in starting position and a stop is equal to the value represented by the stop plus unity. When the racks are in the starting position, the minimum gap G between the racks and the stops is one step. Thus, if the value associated with a stop is N, then the distance A from a rack in the starting position to this stop is made equal to: $A=N+1$.

Racks 20 are maintained in their starting position against the tension of their springs 19 by a restoring bar 25. At the start of the value-entering operation the restoring bar 25 is moved quickly to the left as viewed in Fig. 1, in a manner fully described hereafter, and at the same time a driving bar 170 moves to the left so as to drive the racks 20 positively across the gap G. This movement of the drive bar is relatively fast; it serves to accelerate the racks rapidly and to send them positively on their way towards the settable stops 0-9. Drive bar 170 comes to a stop after having pushed the racks one step, and the racks continue to move towards the stops due partly to inertia and partly to their springs 19. When a rack tip 26 reaches the associated stop, the rack comes to a rest; any rebound may be prevented by a ratchet pawl 171 rockable on a shaft 172 under the influence of a spring 173. Prior to the return stroke of the racks 20 the ratchet pawls 171 are disengaged from the racks by a cross-bar 174, in a manner to be described in due course; the restoring crossbar 25 and the driving bar 170 move back, and the restoring bar 25 picks up the racks 20 and restores them to the starting position, preferably against a fixed stop bar (not shown).

As the original inertia of the racks 20 is overcome by the driving bar 170, the springs 19 attached to the racks have to overcome only the frictional resistance of the racks and associated parts, and the drag of the rebound pawls 171. Consequently, these springs 19 may be relatively weak, and the total load may be considerably reduced in comparison with a conventional arrangement wherein the springs have to overcome the original inertia of the driven parts. If the driving bar 170 is sufficiently fast, the acceleration applied to the racks 20 may be sufficient to propel the racks through the remainder of their stroke, and the springs 19 may be omitted altogether. If desired, there may be a gap between the driving bar and the racks when in the starting position, and the driving bar 170 may move more than one step in order to produce a hammer-like action and to accelerate the racks rapidly.

As shown in Figs. 1 and 2, a gear 17 is arranged adjacent to each rack 20; gears 17 are rotatable on shaft 18 fixedly supported in the machine structure 12, 13. Each gear 17 meshes with a pinion 15 fixed to a totalizer wheel 10 rotatable on a shaft 11. The teeth on gears 17 and racks 20 have the same pitch; the rack pitch line is tangential to the gear pitch circle, and

normally a gap between two rack teeth is aligned with a gap between two gear teeth, the gears 17 being held in this position by means fully described in my said copending specification. Pinions 27 are rotatably mounted on a shaft 28 fixedly held in a support 29; one pinion 27 is aligned with each gear 17 and rack 20 as shown in Fig. 2, and its width is approximately equal to the combined width of gear 17 and rack 20. Pinions 27 are normally held by a stationary aligner bar 175 in such a position that a tooth on each pinion points towards the said aligned gap between two adjacent teeth on the respective gear 17 and rack 20, the pinions being just out of mesh with gears and racks. In order to couple racks 20 to gears 17, pinion shaft 28 is moved bodily upwards, in a manner fully described hereafter, so that a tooth on each pinion 27 enters the said gap between teeth on the associated gear and rack. When pinions 27 are fully in mesh with gears and racks, they are free of the aligner 175; thus, a driving connection is established between racks 20 and gears 17.

Prior to an additive value-entering operation pinions 27 couple racks 20 to gears 17, whereupon racks 20 are caused to move on to stops 0-9 as described, thereby driving the totalizer wheels 10 additively (anti-clockwise as viewed in Fig. 1) in accordance with the values represented by the respective stops plus unity. At the end of forward stroke of racks 20 pinions 27 are demeshed from racks 20 and gears 17, whereupon racks 20 are restored to their starting position by the restoring bar 25. During a subtractive value-entry pinions 27 couple racks 20 to gears 17 only after the forward stroke of racks 20, so that racks 20 drive during their return stroke the totalizer wheels 10 subtractively (clockwise as viewed in Fig. 1).

On completion of the value-entering operation the carry is effected in a manner fully described in the specification to my said co-pending patent application. It is sufficient to state here that during the carry operation those totalizer orders which do not require a carry are moved back one step, since all values to be entered into the totalizer have been automatically increased by unity due to the provision of the gap G, as described above. Those totalizer orders which do require a carry remain stationary during the carry operation, since they have been already advanced one step in excess of the actual value to be entered.

As it is well known in the art of calculating machines, racks 20 and settable stops 0-9 may be arranged to be relatively displaceable transversely of the machine; in such a case the provision of a substantial gap G according to the present invention is of advantage in order to facilitate this transverse displacement.

The operating mechanism will now be described. The machine is operated by a main driving shaft 76, Figs. 1 and 4, suitably journaled in the supporting structure 12, 17 and rotated once during each operating cycle by a suitable handle or motor (not shown).

Referring to Fig. 3, the mesh-demesh operation of pinions 27 is controlled by a grooved cam 78 fixedly mounted on main shaft 76. Cam 78 co-acts with a roller 79 journaled in a follower 80 fixedly mounted on a shaft 81 journaled in the supporting structure 71, 82, Fig. 4. An arm 83, Fig. 3, is fixedly mounted at each end of shaft 81; each arm 83 has a pin-and-slot connection 84 to a lever 85 rockable on a trunnion

86 fixedly supported in machine frames 11, 82, Fig. 4, respectively. Pinion shaft support 29, Figs. 1 and 3, is fixed at each end to one of levers 85. During addition the main driving shaft 76 is rotated clockwise as viewed in Fig. 3, and early in the cycle cam 78 causes its follower 88 to rock anti-clockwise, which causes levers 85 and support 29 to rock clockwise around trunnions 86 and thus to mesh pinions 27 with gears 17 and racks 20, as described. The parts remain in this position until shortly before the racks 20 start on their return stroke; now cam 78 restores follower 88 and support 29, so that pinions 27 are demeshed from racks 20. During subtraction the main shaft 76 is rotated anti-clockwise; at about the middle of the cycle cam 78 rocks its follower 88 anti-clockwise, thus meshing the pinions 27 with racks 20 and gears 17. Near the end of cycle cam 78 restores the follower 88, and pinions 27 are again demeshed from racks 20 and gears 17.

Driving bar 170 protrudes through slots in machine frames 12, 13 and is at each end secured to a bracket 176, Fig. 3, fixedly mounted on a sleeve 92, Fig. 1, rotatable on shaft 81. Fixedly mounted on sleeve 92 is an arm 177 which has a roller 178 maintained by a spring 179 in contact with a cam 180 fixedly mounted on shaft 76. Cam 180 is so shaped that early in each operating cycle it causes the follower 177 and brackets 176 to rock sharply anti-clockwise around their shaft 81; this results in a corresponding movement of driving bar 170, which starts the racks 20 on their forward stroke as described. An overthrow of driving bar 170 may be prevented by a fixed stop 181, Fig. 3. During the second half of cycle the cam 180 restores the driving bar 170. Cam 180 is symmetrical and operates the driving bar 170 in exactly the same manner during both additive and subtractive revolutions of shaft 76.

Similarly, the restoring bar 25 is operated in like manner both by counter-clockwise and clockwise revolutions of main shaft 76. Restoring bar 25 protrudes through suitable slots in machine frames 12, 13, and is fixed at each end to an angle bracket 182, Fig. 4, guided by rollers 183 in rails 184 secured to frames 12, 13, respectively. Each bracket 182 has a pin 185, see also Fig. 3, engaging a slot in an arm 186 fixedly mounted on a shaft 187 suitably journaled in machine frames 12, 77. A cam follower 188, Fig. 1, is fixedly mounted on shaft 187; it has two rollers 189 coaxing with a double cam 190 fixedly mounted on main shaft 76. When shaft 76 is turned in either direction, cam 190 causes shaft 187 and arms 186 to rock anti-clockwise. In consequence, brackets 182 and bar 25 are caused to slide to the left as viewed in Fig. 1, thus allowing the racks 20 to move during their forward stroke as described. Bar 25 reaches its extreme left-hand position shortly before the middle of cycle, and after a short space of time required for the mesh-demesh operation of idlers 27 described above, bar 25 is restored by its cam 190. As the bar 25 moves to the right, it picks up racks 20 and restores them into their starting position.

As already mentioned, rebound-preventing pawls 171, Fig. 1, are disengaged from racks 20 prior to return stroke of the latter by a crossbar 174. This bar 174 is fixedly mounted on two brackets 191 rotatable on shaft 172. One of brackets 191 has an extension 192 adapted to be latched by a latch 193 rotatable on a sleeve 158

on shaft 141. A spring 194 anchored at 195 in the supporting structure normally presses the lower end 196 of latch 193 against a pin 197 secured in the double cam 190. Pawls 171 are normally in engagement with racks 20. Shortly before the rack restoring bar 25 reaches its extreme left-hand position (as viewed in Fig. 1), two abutments 198 on bar 25 contact extensions 199 of brackets 191 and cause the brackets to 10 rock anti-clockwise. This causes bar 174 to rock around shaft 172 so as to disengage all pawls 171 from associated racks 20. At the same time latch 193, which is now not supported by its pin 197, rocks slightly due to spring 194 and latches the restoring bar 174 in the "restore" position, in which it remains until the end of return stroke of racks 20. Shortly before the end of cycle pin 197 re-engages end 196 of latch 193 and rocks it 15 slightly clockwise; latch 193 delatches bar 174 which releases the pawls 171. Due to their springs 173 pawls 171 now re-engage the racks 20 in 20 readiness for the next operating cycle.

It will be apparent to those skilled in the art that the device hereinbefore described may be 25 readily modified without departing from the spirit of the present invention. Thus, springs 19 driving the reciprocating racks 20 may be replaced by single or double resilient plungers or rockers co-acting with suitable abutments on the racks, or by suitable frictional devices. Straight-line racks may be replaced by rotary segments. In machines adapted for irregular numerical systems such as Sterling the actual size of the gap G between the various racks and the settable stops, and/or the amount of positive displacement applied to the racks associated with different denominations by the driving bar 170 or its equivalent, may be selected to suit the different conditions. The invention may be advantageously applied to reciprocating devices 30 adapted to sense the presence or absence of settable stops.

What I claim is:

1. In a machine of the type referred to having 35 selectively settable stops representing numerical values: a plurality of reciprocating elements normally located in a starting position, the distance between each element when in the starting position and the associated stop being representative of the value represented by the respective stop plus unity, a driving member for positively driving all said elements through a distance substantially representative of unity, individual resilient means each associated with one of said elements for yieldingly driving the associated element on to the respective stop, and a restoring member for positively restoring all said elements into the starting position.

2. A machine according to claim 1, further 40 comprising means for preventing a rebound of the said elements when they contact their respective stops.

3. A machine according to claim 1, further 45 comprising means for reciprocating the said driving member during each operating cycle at least through a distance representative of unity.

4. A machine according to claim 1, further 50 comprising means for reciprocating the said restoring member during each operating cycle at least through a distance corresponding to the maximum stroke of any one of said elements.

5. In a machine of the type referred to having 55 selectively settable stops representing numerical values: a value-entering device comprising a plurality of reciprocating elements arranged in

operative association with the said stops, means for driving the said elements positively through a part of their forward stroke and yieldingly through the remainder of their forward stroke, and means for positively restoring the said elements during their return stroke.

6. In a machine of the type referred to, a plurality of reciprocating elements in operative association with settable stops, means for driving the said elements positively through a part of their stroke towards the said stops and yieldingly through the remainder of their stroke, means for preventing a rebound of the said elements on

reaching the respective stops, and means for positively restoring the said elements into their starting position.
